UNITED STATES PATENT OFFICE.

HENRY SYMONDS, OF LONGBEACH, CALIFORNIA, ASSIGNOR TO FRANK
GEO. BUTLER, OF LONGBEACH, CALIFORNIA.

ACETYLENE-GAS GENERATOR AND CONTROLLER.

No. 830,465.

Specification of Letters Patent.

Patented Sept. 4, 1906.

Application filed November 9, 1905. Serial No. 286,533.

To all whom it may concern:

Be it known that I, HENRY SYMONDS, a citizen of the United States, residing at Longbeach, in the county of Los Angeles and State of California, have invented certain new and useful Improvements in Acetylene-Gas Generators and Controllers; and I do declare the following to be a full, clear, and exact description of the invention, such as will enable others skilled in the art to which it appertains to make and use the same.

This invention relates to acetylene-gas generators and controllers; and one of the principal objects of the same is to provide simple, reliable, and efficient means for automatically feeding carbid to the generator and to provide means for regulating the feeding of the carbid by the action of the gasometer-bell in the gasometer.

20 This and other objects are attained by means of the construction illustrated in the accompanying drawings, in which—

Figure 1 is a side elevation and partial section of a generator and gasometer made in accordance with my invention. Fig. 2 is an enlarged sectional view of the carbid-feed valve, and Fig. 3 is a detail view and partial section of the mechanism for operating the carbid-feed valves.

30 Referring to the drawings for a more particular description of my invention, the numeral 1 designates the generator-tank, which is provided with a conical bottom 2, having a discharge outlet-pipe 3 leading from the lower end thereof out through the wall 4 and provided with a valve 5, adapted to be actuated by automatic means for discharging the residuum or spent carbid at certain intervals-dependent upon the condition of gas-pressure in the gasometer, as will presently appear. A partition 6 is formed near the upper end of the generator, and a gas-outlet chamber 7, having a closed upper end, extends into the partition 6. Depending from the partition 6 is a water-inlet pipe 8, having its lower end perforated, as at 9. Above the partition 6 is a float-valve chamber 10. A water-supply inlet-pipe passes through the valve 12, actuated by means of a float comprising a ball 13, an arm 14, extending from the ball to a yoke 15, connected to the valve-stem 16 to operate the same by means of the

water-level in the chamber 10 to discharge water through the pipe 17 into the chamber 10 and through the pipe 8 into the generator-chamber 1. Owing to the size of the perforations 9 in the pipe 8, water will be maintained in said chamber 1 at a certain predetermined height, and at the same time water in the chamber 10 will also reach a certain level. An overflow or surge chamber or compartment 18, provided with an outlet-pipe 19, is in direct communication with the generator-tank at a point 20, the purpose of the said surge-chamber being to prevent an overcharge of water within the generator under certain conditions. A gas-outlet pipe 21, having its inlet end 22 within the outlet-chamber 7 above the water-line, leads downward and out of the generator to a cleaning device, presently to be described.

The carbid-feeding device, comprising a chamber 23, having a frusto-conical upper and lower end, is supported upon a hopper or neck 24, which extends through the water-chamber 10 and is open at its lower end directly into the generator-chamber 1. This hopper 24 has secured to its upper end a carbid-chamber 23 by means of suitable flanged clamps 25. Within the chamber 23 is a cap 26, closed at its upper end and open at its lower end, as shown, said cap being supported from within the chamber 23 by suitable means, as by arms 27. A valve 28 is mounted to slide within the cap 26 at its upper end, while its lower end is adapted to slide within the tubular lower end 29 of the chamber 23. Connected to the lower end of the valve 28 is a stop-valve 30, the upper end of which is frusto-conical, as shown, and said stop-valve 30 is connected to the valve 28 by a rod 31. Said valves 28 and 30 thus operate simultaneously, as will be hereinafter described. Extending downward through the stop-valve 30 is a stem 32, supported at its end upon a lever 33, pivoted at 34 within an extension 35, formed on the hopper 24. On the outer end of the lever 33 a roller 36 is journaled, said roller adapted to travel upon a cam-wheel 37, fixed to a shaft 38, journaled in a frame 39. The lever 33 has a handle 40, by which it may be operated by hand, if desired. Mounted in the frame 39 is a drum 41, around which a cord or cable 42

is passed, and connected to the lower end of said cable is a weight 43, said weight being disposed immediately in front of a vertical scale 44, containing certain marks to indicate the condition of the generator, as will herein-after appear. On the end of the drum 41 is a crank 45, by means of which the weight may be raised. A gear-wheel 46 is mounted on the crank-shaft and is in mesh with a gear 47 on the shaft 38 of the cam-wheel 37, while the gear 47 is in mesh with a gear 48 on a shaft 49, carrying a brake-wheel 50. A brake-lever 51, pivoted at 52 and provided with an adjustable weight 53, is provided 15 with a depending arm 54, adapted to be brought into contact with the brake-wheel 50 to cut off the feed of carbid to the generator when the gasometer-bell ascends beyond a certain point and to release the brake-wheel upon the descent of the gasometer-bell, as will be understood. A chain 55 is attached at one end to the lever 51 and at the opposite end to the top of the gasometer-bell.

25 The gasometer comprises a condensing chamber 56, separated from the gas-chamber 57 by means of a partition 58. The gasometer-bell is fitted to operate within a water-jacket in the usual manner. A gas-filter 60, 30 having its lower end discharging near the bottom of the condenser-chamber 56 and its upper end extending above the water-level in the gasometer and passing through the partition 58, is partially filled with suitable filtering material 61, held therein by means of a wire-gauze cap 62. The gas passing through the pipe 21 is led into the filter 60 and discharges into a flaring outlet-nozzle 63 within the filter 60, the gas then rising through the 35 filtering material 61 and passing upwardly into the gasometer-bell 59. Water is supplied to the gasometer-bell and condenser-chamber by means of a pipe 64, having a valve 65, which may be opened to supply 40 water to both the condensing-chamber and above the partition 58. A filter-pipe 66, similar in construction to the pipe 60, leads the gas from the gasometer-bell 59 downward through filtering material 67 and out 45 through a service-pipe 68 to the burners. At the top of the carbid-chamber 23 is a cap or cover 69, connected to a yoke 70 and held in place by means of a lever 71, pivoted at 72, and a link 73, bolted to a keeper 74 at the 50 top of the carbid-chamber 23. The lever 71 is provided with a toe 75, adapted to engage a pivot-hook 76 to hold the cap or cover 69 in place. A string or cord 77 is connected to one end of the lever 71, and the opposite end 55 of said cord is connected to a weighted lever 78, pivoted upon a bracket 79 and provided with a projection 80, said projection adapted to come into contact with the face of the cam-wheel 37 to stop the feeding of carbid at a

time when the cap or cover 69 is removed 65 from the chamber 23 or when said chamber is being filled with comminuted carbid. The valve 5 is provided with a stem 81, to which is connected a lever 82, and pivoted to the lever 82 is a weighted arm 83, connected at 70 one end to a rod 84, upon the upper end of which is a roller 85, adapted to be actuated by the cam-wheel 37 to open the valve 5 and discharge the spent contents of the generator at a time when the supply of gas in the gas- 75 meter is low, as will be understood.

A blow-off pipe *a*, provided with an outlet-pipe *b*, located in line with the condenser-chamber, is provided as a means of preventing the accumulation of an excess of gas in 80 the condenser.

The operation of my invention may be described as follows: Water having been fed to the generator-chamber and to the chamber 10 through the valve 12 and water having 85 been fed to the gasometer through the pipe 64 and the weight 43 having been wound up, the service-pipes in the building are now opened to allow the air to escape from the gasometer before the feeding of the carbid 90 commences. The handle 40 will now be operated to feed carbid to the generator and to commence the generation of gas. The gas generated passes through the outlet-pipe to the cleaner, up through the cleaner to the 95 gasometer-bell, and thence down the filter-pipe to the outlet or supply pipes. When the gasometer-bell ascends, it actuates the lever which controls the feeding mechanism, as will be understood. The valve 28 is raised 100 by the mechanism until the stop-valve 30 occupies a position in the lower end 29 of the carbid-chamber, the carbid then being fed downward upon the upper end of said stop-valve. As the valve drops the carbid is deposited in the generator through the hopper 24, as will be understood, the valve 28 then remaining in its lowermost position and stopping the feeding of carbid until it is again 105 raised by the mechanism actuated by the 110 cam-wheel 37 to again feed the carbid.

Various changes in the form, proportion, and the minor details of construction may be resorted to without departing from the principle or sacrificing any of the advantages of 115 this invention.

Having thus described my invention, what I claim as new, and desire to secure by Letters Patent, is—

1. In an acetylene-gas generator, a carbid-feed comprising a cap, a valve sliding in said cap, a stem projecting from said valve, a stop-valve on said stem, a lever supporting said stem, a roller on said lever, a cam-wheel mounted in a frame and actuated by a weight 120 for operating the feed-valve, substantially as described.

2. A carbid-feed comprising a carbid-feed

chamber, a cap in said chamber, a valve adapted to move in said cap, a stem on said valve, a stop-valve on said stem, a pivoted lever for supporting said stem, and a cam-
5 wheel actuated by a counterweight, and means for braking said cam-wheel, substantially as described.

In testimony whereof I have hereunto set my hand in presence of two subscribing witnesses.

HENRY SYMONDS.
